UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,836, dated December 4, 1894.

Application filed October 29, 1894. Serial No. 527,359. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or other woven fabric is clearly illustrated in the accompanying drawing.

10 The main feature of the design is the arrangement and composition of the wide and narrow stripes.

The wide stripe R has a well defined dark stripe r and on each side of this dark stripe 15 are two narrow dark stripes r' separated from the central stripe r by narrow light stripes r^2 and tinted stripes r^3 . Beyond the dark stripes r' are tinted stripes r^4 .

The narrow stripe S is composed of two very 20 narrow dark stripes s and a tinted stripe s' .

The tinted back ground T separates the several stripes R and S and on each side of the stripes R, in the back ground, is a white stripe t , and at each side of the stripes S is a white stripe t' , giving the effect clearly shown 25 in the drawing.

I claim—

The design for woven fabric as herein described and clearly shown in the accompanying drawing.

In testimony whereof I have signed my name to this specification in the presence of two subscribing witnesses.

JOHN B. MORGAN.
